EASY OPENING, RECLOSEABLE CONTAINER

Clyde H. Bloedorn, Evanston, Ill., assignor to Continental Can Company, Inc., New York, N. Y., a corporation of New York

Application November 2, 1943, Serial No. 508,729

3 Claims. (Cl. 220—60)

The invention relates generally to container structures formed of metal and primarily seeks to provide a simple and inexpensively constructed container having a novel form of end closure which provides an efficient hermetic seal and yet can be readily pried off the container and then replaced at will to effect a reclosure of said container.

In its more detailed nature the invention resides in providing in a container of the character stated a body having at its open end an outwardly turned hem, and a cover having a heel portion snugly fitting in said open end and an outwardly turned flange terminating in an inwardly turned hook or bead, said flange having a sealing compound applied over its under surface and extending from a point on the outer wall of the heel over to and in contact with the inwardly turned extremity of the hook or bead, and said flange in the closing of the container being turned or rolled against the body end portion, as by a first operation seaming roll action, to press the sealing compound over and against the body end hem and the cover hook or bead in cover locking engagement under said hem.

Another object of the invention is to provide a container of the character stated in which the hem equipped open end extremity of the body is slightly flared and the cover heel slightly tapered to snugly fit the flare so that when the cover hook is pressed in locking engagement under the body hem the cover flange rolled over the body hem is held in tension with the tapered cover heel engaging in tight sealing contact in its flared body seat.

With the above and other objects in view that will hereinafter appear, the nature of the invention will be more fully understood by following the detailed description, the appended claims and the several views illustrated in the accompanying drawing.

In the drawing:

Figure 1 is a side elevation and part cross sectional view illustrating a container structure embodying the invention.

Figure 2 is an enlarged fragmentary cross sectional view illustrating a portion of the container body and an end closure in position for being applied thereon.

Figure 3 is a view similar to Figure 2 and illustrates the closure assembled in hermetic sealing contact on the container body.

In the container structure herein disclosed as an example of embodiment of the invention there is included a body 5 which is closed at one end

as by the usual closure 6 secured by a double roll seaming operation. The open end edge of the container body is turned outwardly upon itself in the form of a tight hem 7, and it will be observed by reference to Figures 2 and 3 that the hem equipped open end extremity of said body is slightly flared as at 8 to provide a cover heel seat. The hem 7 defining the open end of the container body gives rigidity to said end, avoids the provision of raw edge portions at the mouth of the container and also provides a lock shoulder as will hereinafter appear.

The container cover or end closure is provided with a centrally depressed body portion 9 which merges into a slightly tapered, flared seat engaging heel 10 insertable into the end of the container body and which in turn merges into an outwardly turned flange 11. The flange edge extremity is turned under in the manner clearly illustrated in Figure 2 to provide a hook or bead 12, and it will be observed by reference to said Figure 2 that a sealing compound 13 is applied to the under surface of the flange starting from a point 14 on the outer surface of the heel 10 and extending over to and in contact with the inwardly turned extremity of the hook 12 as indicated at 15.

In effecting the closure or sealing of the container, the slightly tapered heel 10 of the end closure is inserted in the hem defined open end of the container, so as to engage in the flared body seat 8 and contact the end extremity of said hemmed body opening with the sealing compound 13. With the end closure properly inserted in the open end of the container, the flange 11 is turned or rolled against the hemmed body end in the manner clearly illustrated in Figure 3, as by a first operation seaming roll contact, so as to cause the sealing compound 13 to press in tight hermetic sealing contact over the open end extremity of the hem 7, and also against the outer face of the hem. This downward and inward rolling of the closure flange 45 places the closure hook or bead 12 in position for engaging as a yieldable lock shoulder, as at 16, beneath the hem 7. This yieldable locking of the hook 12 under the hem 7 holds the rolled cover flange 11 in tension with the tapered cover heel 10 engaging in tight sealing contact in its flared body seat 8 and with the sealing compound 13 distributed in two annular pockets as at 17 and 18 one at either side of the annular zone 19 at which said compound is tightly compressed against the endwise and outwardly ex-

tended portion of the hem 7 and forced toward said pockets. See Figure 3.

The closure applied in the manner above described provides an efficient hermetic sealing of the container and can be readily removed by prying contact of any suitable lifting tool, the lock shoulder provided by the bead 11, as at 16, yielding outwardly to a sufficient degree to clear the hem 7. After the container has been initially opened it may be reclosed at will by simply applying the closure over the hem 7 and applying downward pressure thereon to cause the hook or bead 12 to slip down over and lock under said hem.

While the herein disclosed container structure can be adapted for many uses, it is particularly adaptable for the packaging of baby foods because it can be conveniently opened and reclosed in the manner described and without the necessity of applying tools of the nature of the usual can opener and which would be likely to provide metal shavings which might find their way into the container and contaminate products therein.

It is of course to be understood that the details of structure and the arrangement of parts may be variously changed and modified without departing from the spirit and scope of the invention.

I claim:

1. In a container, a body having an open end defined by an outwardly turned hem, a cover of the pry-off type having a heel portion insertible in said open end and an outwardly turned flange terminating in an inwardly turned bead, and sealing compound applied to the under surface of said flange only and extending from said heel portion over to and in contact with the inwardly turned extremity of said bead, said flange extending outwardly and downwardly about the hemmed end of the container in position for pressing the sealing compound in tight sealing contact over and against the outer face of said hem with the inwardly turned portion of the cover bead engaging in metal to metal contact

with and extending under the lower extremity of said hem as a yieldable lock shoulder.

2. In a container, a body having an open end defined by an outwardly turned hem, a cover of the pry-off type having a heel portion insertible in said open end and an outwardly turned flange terminating in an inwardly turned bead, and sealing compound applied to the under surface of said flange only and extending from said heel portion over to and in contact with the inwardly turned extremity of said bead, said flange extending outwardly and downwardly about the hemmed end of the container in position for pressing the sealing compound in tight sealing contact over and against the outer face of said hem with the cover bead engaging as a yieldable lock shoulder under said hem, said hemmed body end being slightly flared to form a closure heel receiving seat and said closure heel being tapered to snugly fit said seat and be securely held thereon by the lock shoulder engagement of the cover bead under said hem.

3. In a container, a body having an open end defined by an outwardly turned hem, a cover of the pry-off type having a heel portion insertible in said open end and an outwardly turned flange terminating in an inwardly turned bead, and sealing compound applied to the under surface of said flange only and extending from a point on the outer wall of said heel portion to and in contact with the inwardly turned extremity of said bead, said flange extending outwardly and downwardly about the hemmed end of the container in position for pressing the sealing compound in tight sealing contact over and against the outer face of said hem with said compound distributed in two annular pockets one at either side of a central highly compressed annular zone against the endwise and outwardly extended portion of the hem, and spaced a distance from said bead and with the inwardly turned portion of the cover bead engaging in metal to metal contact with and extending under the lower extremity of said hem as a yieldable lock shoulder.

CLYDE H. BLOEDORN.
